FIG. 7

CONTROL CIRCUIT FOR LOAD HAVING MEASUREABLE COEFFICIENT OF RESISTANCE

BACKGROUND OF INVENTION

The present invention relates to a control circuit wherein a separate sensor is not required to detect the condition of the load being controlled. Prior art devices of this type have not provided satisfactory means for eliminating noise factors because of AC line switching. Nor, have the prior circuits provided for operation with DC sources of power such as found in automobiles, trucks, aircraft, etc.

Moreover, such circuits have not had means for automatic shut-down of the circuit should the load become short-circuited or draw current in excess of selected values.

SUMMARY OF INVENTION

The present invention eliminates noise and resolution problems inherent with AC circuit applications in controls wherein the load also acts as its own sensor by providing a novel means of switching at or near the zero crossings of the AC supply. This is accomplished by sending a sampling pulse through the load as the AC voltage is close to a zero voltage crossing. The invention also provides for the automatic shut-down of power to the load by a safety circuit which is referenced to the maximum load current desired and shuts the circuit down in the event it is overloaded or short-circuited.

DESCRIPTION OF DRAWINGS

FIG. 1 is a schematic circuit illustrating the principles of the invention.

FIG. 2 is a DC wave form taken from a full wave rectified AC supply.

FIG. 3 is a wave form which is used as a pulsing signal initiated as the DC wave of FIG. 2 approaches the zero crossing of its AC supply.

FIG. 4 shows the wave form of the pulse power or current applied to the load when the load is above its control point.

FIG. 5 is a wave form of the power or current applied to the load when the load is below its control point and requires full power.

FIG. 6 is a combination of the wave forms shown in FIGS. 4 and 5 wherein the load is under simulated actual "on" and "off" controlling conditions, and

FIG. 7 is a schematic view of an alternate embodiment of the invention wherein a DC supply is used instead of an AC supply.

PREFERRED EMBODIMENTS

Reference is now made to FIG. 1 of the drawings which shows a representative circuit embodying the concepts of the invention. While not necessarily limited thereto, the circuit indicated at 10 is described in conjunction with the temperature control of a heater load 11. The load has a measureable temperature coefficient of resistance; in the present case it has a positive coefficient. In other words, the higher the temperature the greater the load resistance. As shown in FIG. 1, the embodiment includes a power supply 12, a pulsing or sampling signal source 13, a power control or switching circuit 14, a monitoring circuit 15, a comparator circuit 16, and a safety shut-down circuit 17.

Power is applied to the power supply 12 in the form of an AC voltage coupled to a bridge rectifier 19. The unfiltered DC output of rectifier 19 via lines 20 and 21 is shown in FIG. 2. This, at the appropriate time, is switched to the load 11 by the power control circuit 14.

A filtered and zener regulated voltage source for the various control circuits is supplied from a capacitor 23, resistor 24 and zener diode 25. The regulated voltage, in one instance, is applied via leads 26 and 27 to the 10 amplifier 28 in the pulsing circuit 13.

Amplifier 28 may be of the DC high gain integrated circuit type having a plus input 29 and a minus input 30. In this application, a plus input (non-inverting) passes the signal to the amplifier output without changing polarity. The minus input (inverting) passes the signal to the amplifier output but reverses its polarity.

A sampling or pulse signal indicated at 31 (FIG. 3) is generated by the amplifier 28. The pulse signal output 31 is made to trigger as the output 32 (FIG. 2) from 20 the bridge rectifier 19 approaches zero (Point 33, FIG. 2); in other words as the AC line input from terminals 18 nears or approaches the zero voltage crossings thereof.

To achieve the pulse 31, the positive input at amplifier terminal 29 is referenced to the voltage level of 25 about 5 volts across resistor 34. It is derived from the regulated supply including the zener 25 and may be typically set at about 5 volts by the voltage divider resistors 34 and 35.

30 Negative input 30 of the amplifier is coupled to the bridge rectifier output 20 and receives the unfiltered full wave DC voltage 32 (FIG. 2). Thus, when the unfiltered voltage 32 approaches the zero voltage level, and is less than the voltage divider input voltage at terminal 29, amplifier 28 will achieve its most positive voltage state. This results in the pulsed amplifier output as 35 shown at 31 (FIG. 3). When the unfiltered full wave DC voltage 32 exceeds the reference voltage across resistor 34, there will be zero output from amplifier 28.

40 For the purpose of energizing the power control circuit 14, the amplifier sampling signal or pulse 31 is applied through conductor 36 to the base 37 of a transistor 38. Output current of transistor 38 is applied to a transistor 39 which in turn causes a transistor 40 to 45 switch or conduct at pulsed intervals. The transistor 40 has its output circuit coupled between the full wave DC power supply line 20 and the monitoring circuit 15 (the latter containing the load 11).

45 In function, each time the amplifier 28 sends out a pulse 31 (FIG. 3), the power control circuit 14 switches on for the same duration. Current pulses as shown by the solid lines 41 in FIG. 4 are then applied to the monitoring circuit 15 and load 11. As shown in FIGS. 2-4, the current pulses 41 occur near or at the zero voltage 50 crossings of the supply voltage.

55 As shown in FIG. 1, the monitoring circuit 15 includes a bridge 42 having the load 11 in one leg, followed by a low value resistor 42 in an adjacent leg, a resistor 43 in the next leg, and a resistor 44 and resistance potentiometer 45 in a fourth leg. Resistor 42 must pass all of the load or heater current; for high efficiency and minimum power loss it is typically less than 1/10 the resistance of the load 11. It thus acts as a current shunt.

60 To detect the condition of the monitoring circuit 15, the bridge output at points X and Y is coupled to the comparator circuit 16 and its amplifier 46. The ampli-

fier 46 is used as a switching differential comparator. It acts as a switch by using a positive feedback resistor 47 to return a portion of the amplifier output to the plus input 48.

When the bridge output voltage at point Y is, for example, 10 millivolts more positive than the voltage at point X, the amplifier 46 output will be at its most positive value. It will stay in such condition until the voltage at point X is slightly more positive than the voltage at point Y. By the amplifier switching from a low to a high output in response to the output of the bridge 42', the comparator circuit provides an indication of the bridge condition.

In operation, assume the load resistor 11 is a heater being controlled and it is below the temperature set by the potentiometer 45. In such case, the resistance of the load 11 is low and the pulse 41 (FIG. 4) applied thereto will appear more positive at Y than at X. Amplifier 46 will then switch to its more positive output value which is then applied via conductor 49 to the base 37 of the transistor 38. Transistor 38 is now held in a conductive mode thereby turning on transistors 39 and 40. Full wave rectified DC voltage at 50 (FIG. 5) is then applied to the monitoring circuit 15 including the bridge and heater 11. Initial power switching via the pulse 41 is always done near or at the zero crossings of the AC supply voltage to reduce the generation of RFI effects.

As the load 11 increases in temperature its resistance will increase. Current through the load will then decrease as will the voltage at point Y.

When the voltage at point Y reaches a level just slightly less than point X, amplifier 46 will switch to its low state. This turns off transistors 38, 39 and 40 in the power control circuit 14. The power control circuit will then stay off until the next sampling pulse 41 at half wave intervals causes it to turn on momentarily.

If the load is too hot, the amplifier 46 will stay in its low state and no further power (except for the pulse 41) will be applied to the load for the remaining portion of the half wave supply cycle. The wave form of the pulse 41 applied to the heater is shown in FIG. 4 for the condition of the heater or load being above the set-point temperature. Dotted lines 51 indicate the time the power is off.

Once the heater 11 has cooled sufficiently to provide the predetermined positive output from the bridge at point Y, the amplifier 46 will turn on the power control circuit 14 via conductor 49. Full wave unfiltered DC voltage is then applied to the heater load 11 as shown at 50 in FIG. 5.

After the load has reached its set-point temperature, the power applied to the load may take the form shown in FIG. 6. The ratio of "on" to "off" time to keep the heater at the correct average temperature will depend on the condition being controlled. Excellent control resolution is achieved since the power control means 14 may be turned off at any point in the voltage cycle. An example is shown in FIG. 6 wherein comparator circuit 16 detects point X being more positive than Y midway in the cycle as indicated at 52 and immediately shuts off the power control circuit 14. This can occur at any point in the half cycle (except for the pulse period 41).

As another feature of the invention, means are provided through the safety circuit 17 for the automatic shut-down of the load 11 should it become short-

circuted or over-loaded. Safety circuit 17 includes a positive or regenerative amplifier 53 with a feed back resistor 54. The positive input 55 thereof is coupled via line 56 to one side of shunt resistor 42 so as to monitor the voltage at point Y.

The negative input 57 is coupled to variable resistor 58 tied to bridge rectifier output 21. Variable resistor 58 establishes a reference voltage level on the minus input 57 to keep the output of amplifier 53 in its low output state unless the voltage at Y is more positive and exceeds X by a predetermined level such as when the load in its coldest condition. For example, if the heater is shorted or carries excess current, point Y will be more positive than it would be during its coldest operating design temperature level.

Amplifier 53 then switches to its maximum positive output which is applied to drive transistor 59 into heavy conduction. This diverts current normally supplied to switching circuit transistor 38 by either or both of the amplifiers 28 and 46. The current diversion will turn off transistor 38 thereby turning off the power control circuit 14 and consequently removing power from load 11.

Once amplifier 53 switches to its most positive state, positive feedback via resistor 54 causes it to latch-up and neither the positive nor the negative inputs can affect its high positive output. To place the circuit in operation again, it is necessary to reset by turning the circuit off and then turning it on again. This causes circuit 17 to unlatch.

For use with a DC power supply such as found in automobiles, trucks, aircraft, etc., a unijunction pulser 60 (FIG. 7) or similar relaxation generator device may be substituted for the power supply 12 and amplifier 28. The unijunction pulser would connect at points 61, 62, 63 and 64 in the circuit of FIG. 1. In this embodiment a DC power supply 64' is used to charge a capacitor 65 through a resistor 66. The RC circuit is coupled to the emitter 67 of a unijunction 68. The sampling pulse rate is determined by the characteristics of the resistor and capacitor.

While the invention has been described in conjunction with the controlling of a heater type load, the concepts can also be applied to controlling other loads where the resistance changes with a change in condition. The load is thus used as the sensor to initiate control action.

It is of course obvious that different type amplifiers and voltages may be used than those described hereinabove.

We claim:

1. A circuit comprising,
a power supply,
means coupled to said power supply for supplying a fluctuating DC output,
pulsing means coupled to said means for producing said fluctuating DC output, said pulsing means being adapted to send an energizing pulse when said DC output reaches a predetermined low level, power control means having input and output circuits with the input circuit being energized by pulses from said pulsing means,
a load having a pre-selected coefficient of resistance coupled to the output circuit of said power control means,
means for monitoring the relative resistance of said load and adapted to provide a signal indication

thereof when said power control means is energized by said pulsing means, and 5
comparator means coupled to the output of said monitoring means and coupled to the input of said power control means to energize said power control means independently of said pulsing means when said DC output reaches said predetermined low level.

2. A circuit comprising,
an AC power supply,

means for converting said AC supply to a DC voltage with the DC voltage dropping periodically to a predetermined low value as the AC supply approaches its zero crossings,

pulsing means for generating a sampling pulse which generally coincides with said predetermined DC low value as said AC supply approaches said zero crossings,

a load having a pre-selected coefficient of resistance which changes as the condition of said load changes,

power control means operably connected between said load and said power supply, said power control means having an input and an output, 10
said pulsing means being operably coupled to the input of said power control means so as to energize said power control means when said AC supply is close to the zero crossings thereof to thereby apply power pulses to said load,

monitoring means coupled to said load for determining the relative resistance of said load and adapted to provide a signal as to the condition thereof as 15
said load is energized by said pulsing means, and comparator means coupled to said monitoring means and to said power control means operable to maintain said power control means energized independently of said pulsing means when said load has a predetermined change in resistance.

3. A circuit comprising,

a power supply

pulsing means being adapted to send an energizing pulse at spaced intervals,

power control means having an input and an output with the input being energized by pulses from said pulsing means,

a load having a pre-selected coefficient of resistance coupled to the output of said power control means, monitoring means for determining the relative resistance of said load and adapted to provide a signal indication thereof,

comparator means coupled to the output of said

monitoring means and operatively coupled to said power control means to keep said power control means energized independently of said pulsing means so as to apply power to said load when the load resistance varies a predetermined amount as determined by said monitoring means, and protection means coupled to said power control means for de-energizing said power control means to keep excess current from being applied to said circuit.

10 4. A circuit as claimed in claim 3 wherein said power supply furnishes fluctuating DC voltage and said pulsing means sends a pulse when the voltage drops to a lower level.

15 5. A circuit as claimed in claim 3 wherein said pulsing means includes a relaxation type pulse generator.

6. A circuit as claimed in claim 5 wherein said pulsing means includes a unijunction transistor.

7. A claim as claimed in claim 3 wherein said power 20 supply includes an AC source and wherein said power control means may be turned off at any point in the AC wave.

8. A circuit as claimed in claim 3 wherein said monitoring means includes a bridge and wherein said load is in one leg of said bridge.

25 9. A circuit as claimed in claim 3 wherein said comparator means includes a feed-back type amplifier having its input coupled to said bridge and its output coupled to said power control means.

10. A circuit as claimed in claim 3 wherein said protection means includes means coupled to said pulsing means and to said comparator means to divert current from both of said means to de-energize said power control means.

11. A circuit as claimed in claim 10 wherein said protection means includes a feed-back type amplifier which has its input referenced to a voltage taken from a bridge in said monitoring circuit.

12. A circuit as claimed in claim 3 wherein said protection circuit once energized prevents said power control means from applying power to said load until the circuit is re-set.

13. A circuit as claimed in claim 12 wherein said protection means includes a transistor having its input coupled to the output of an amplifier and its output coupled to the output of said pulsing means and said comparator means.

14. A circuit as claimed in claim 13 wherein said protection means has the amplifier input coupled to said monitoring means.
